(57) **CLAIM**

The ornamental design for a snap hook for a luggage case, as shown and described.

DESCRIPTION

FIG. 1 is a front view of the snap hook for a luggage case embodying our new design, the back view being a mirror image thereof.

FIG. 2 is a right side view of the snap hook shown in FIG. 1.

FIG. 3 is a left side view thereof.

FIG. 4 is a top view thereof; and,

FIG. 5 is a bottom view thereof.
